US0D1085336S

(12) **United States Design Patent** (10) **Patent No.:** **US D1,085,336 S**
(45) **Date of Patent:** **** Jul. 22, 2025**

(54) **CARTRIDGE**

(71) Applicant: **Graco Minnesota Inc.**, Minneapolis, MN (US)

(72) Inventors: **Christopher J. Pellin**, Victoria, MN (US); **Kyle A. Bottke**, Robbinsdale, MN (US)

(73) Assignee: **Graco Minnesota Inc.**, Minneapolis, MN (US)

(**) Term: **15 Years**

(21) Appl. No.: **29/894,997**

(22) Filed: **Jun. 15, 2023**

(51) **LOC (15) Cl.** **08-05**

(52) **U.S. Cl.**

USPC **D23/213**

(57) **CLAIM**

The ornamental design for a cartridge as shown and described.

DESCRIPTION

FIG. 1 is a first isometric view of a cartridge;
FIG. 2 is a second isometric view of the cartridge;
FIG. 3 is a third isometric view of the cartridge;
FIG. 4 is a fourth isometric view of the cartridge;
FIG. 5 is a front end view of the cartridge;
FIG. 6 is a rear end view of the cartridge;
FIG. 7 is a right side view of the cartridge;
FIG. 8 is a left side view of the cartridge;
FIG. 9 is a top plan view of the cartridge; and,
FIG. 10 is a bottom plan view of the cartridge.
The broken lines in the Figures represent portions of a cartridge and form no part of the claimed design.

1 Claim, 10 Drawing Sheets
